UNITED STATES PATENT OFFICE.

GEORGE L. BEERS, OF WILKINSBURG, PENNSYLVANIA, ASSIGNOR TO WESTINGHOUSE ELECTRIC & MANUFACTURING COMPANY, A CORPORATION OF PENNSYLVANIA.

COIL MOUNTING.

Application filed January 2, 1926. Serial No. 78,792.

My invention relates to the mounting of inductances such as are used in radio receiving or transmitting systems and has particular reference to the mounting of such coils 5 when they are to be used in small places.

The principal object of my invention is to devise methods of and means for, mounting a plurality of inductances in close relation whereby the inductive coupling there- 10 between will be held at a minimum.

A further object of my invention is to provide means whereby the relative positions of such inductances may be changed and,

A still further object of my invention is 15 to provide an inductance mounting which will be easy to assemble and which will hold the inductance firmly in position.

It has been found, when building a radio receiving or transmitting set, that very often 20 undesired couplings exist between the component inductances, which is an obvious disadvantage. It has also been found necessary in the construction of portable receiving sets to place coils belonging to different circuits 25 in rather close relation. This, of course, results in undesired inductive coupling between the coils.

It is old and well known that coils may be 30 connected astatically so that the outside field is reduced to a minimum. With these conditions in mind, I have designed a mounting whereby an astatic coil in, for example, the plate circuit of one tube may be placed rather close to a coil which might be in the grid circuit of the same tube or in the grid or plate 35 circuit of another tube and, at the same time, I am enabled to avoid undesired coupling between these two sets of inductance. To accomplish this result I so locate an astatic in- 40 ductance composed of two sections, with reference to a single inductance, that the inductive effect of each half of the astatic inductance on the single inductance is neutralized.

I have also devised a method of mounting 45 the various inductances involved in this system in such manner that they will at all times be firmly held in position, will not be subject to deformation, and may be easily assembled. I accomplish these results by 50 employing inductances of the spider-web or basket-wound type and attaching them flat against an insulating support, using as an attaching means a continuous strand of cord or analogous material.

For a more complete understanding of my 55 invention, reference is made to the accompanying drawings forming a part of this specification in which,

Figure 1 is a plan view of a preferred form 60 of my astatic system;

Fig. 2 is a cross section of the same on the line II-II;

Fig. 3 is a detail view of the astatic inductance assembly;

Fig. 4 is a back view of the assembly show- 65 ing the manner in which the inductances are attached to the support.

In Fig. 1, inductances 1 and 2 are positioned astatically. In other words these inductances are both wound in the same direction and 70 the outer ends are connected together at 3. These inductances are firmly secured to an insulating support 4 by means of a filiform element 5 which is more clearly shown in Figs. 3 and 4. The second inductance 6 is 75 positioned below the first inductance assembly as shown in Fig. 2 and is spaced therefrom by means of a spacer 7.

The second inductance 6 is also secured to a support 8 by a cord or other element anal- 80 ogous to that by which coils 1 and 2 are held on the support 4. The support 8 is pro- 85 vided with a central opening 9 through which passes the bolt 10 carrying the spacer 7. The aperture 9 is made considerably larger than necessary to pass the bolt 10 and on either side thereof are placed washers 11, which as- 90 sembly permits a relative adjustment of sup- ports 4 and 8.

Referring to Fig. 3, the support 4, of in- 90 sulating material, is provided with a plurality of holes 12 in addition to the central hole. Through these holes is passed the cord 5, which secures the inductances firmly against the insulating support. 95

In Fig. 4, which is a back view of the sup- 100 port 4, is more clearly brought out the manner in which a single continuous cord is used to hold the two inductances against the sup- port.

It will be noted that when a current in any given direction passes through inductance 1, a magnetic field is set up which is opposite in sense to that set up by inductance 2, which is connected astatically to inductance 1. The 105 voltage induced in inductance 6 by inductance 1 is, therefore, opposite in direction to that induced by inductance 2. To secure a

perfect balance, it is usually necessary to shift the position of inductances 1 and 2 along an axis of inductance 6 or perhaps along a chord of inductance 6. This adjustment is provided for by the assembly shown in Fig. 2 in which, by loosening the nut 18 the pressure on washers 11 is released and the upper support 4 is permitted to be adjusted to the desired position.

Referring more particularly to the manner of securing the coils on the support, in Fig. 3 it will be noted that the continuous cord does not pass over the inductance but is threaded through the space left by the winding form peg, enabling this cord to be drawn as tightly as desired, and knotted as shown in Fig. 4.

The entire assembly may be dipped, if desired, into an insulating and moisture resistant varnish or the like, or the coils may, of course, be so treated before mounting. It is obvious that in lieu of the single continuous cord 5 a plurality of separate lengths of cord may be used without departing from the spirit of my invention. It is also obvious that the holes 12 in the insulating plate 4 may be replaced by protuberances around which the cord may be placed.

By this method of astatically positioning three coils, I am enabled to build a receiving set or other radio apparatus having much smaller physical dimensions than when the usual type of inductances are employed. I am also enabled by my invention to quickly position these inductances on their mountings, and to obtain at much less expense than usual, an assembly which is quite durable, compact, and readily replaceable as a unit.

Although I have illustrated and described a single specific embodiment of my invention, certain obvious changes falling within the range of well known equivalents will suggest themselves to those skilled in the art. Accordingly, I do not desire to be limited ex-

cept as required by the prior art and as indicated in the accompanying claims.

I claim as my invention:

1. An inductor assembly for radio-receiving apparatus, comprising a plurality of astatically-connected spirally-wound coils, a second spirally-wound coil, means for supporting said astatically-connected coils in a plane substantially parallel to the plane of said second coil, and means permitting limited lateral motion of said coils in their respective planes, whereby their mutual inductance may be reduced to the lowest value consistent with the vertical distance between the said planes.

2. In combination, two astatically-connected inductors of the spider-web type lying substantially in the same plane with their perimeters closely adjacent, a planar insulating support, filiform means for holding said inductors against said support, a single inductor of the spider-web type having a diameter commensurate with the combined diameters of the two first mentioned coils, and means for positioning the second coil in a plane substantially parallel to the plane in which lie the first mentioned coils and adjacent thereto.

3. In combination, two astatically-connected inductors of the spider-web type, means for supporting said coils in a single plane with their perimeters adjacent to each other, a single inductor of the spider-web type, and adjustable means for movably positioning the second inductor in a plane parallel to the plane in which lie the first mentioned inductors and adjacent thereto, whereby the coupling between said first mentioned coils and the single coil may be adjusted to minimum value.

In testimony whereof, I have hereunto subscribed my name this first day of December, 1925.

GEORGE L. BEERS.
